UNITED STATES PATENT OFFICE.

FRANK H. SCHRYER, OF WAUWATOSA, WISCONSIN.

MAGNETO.

1,385,720.

Specification of Letters Patent. Patented July 26, 1921.

Application filed September 25, 1919. Serial No. 326,231.

To all whom it may concern:

Be it known that I, FRANK H. SCHRYER, a citizen of the United States, and resident of Wauwatosa, in the county of Milwaukee and State of Wisconsin, have invented certain new and useful Improvements in Magnetos; and I do hereby declare that the following is a full, clear, and exact description thereof.

10 My invention relates to new and useful improvements in electricity producing devices for use in connection with the ignition systems of internal combustion engines.

In magnetos used in connection with 15 make-and-break systems of ignition, it has heretofore been more or less difficult to overcome "lag" and to procure a "break" at the moment when the electro motive force is the greatest. It is therefore the primary object 20 of this invention to provide a magneto of the oscillatory type wherein means is provided for overcoming these difficulties and otherwise increasing the efficiency of electric generators for ignition purposes. In 25 this connection the "break" is procured by the direct action of the armature or conductor carrying member itself.

An additional object is to provide an arrangement of parts which will be very compact, this being also occasioned by the relatively few number of such parts, whereby 30 the magneto will require little space on the engine with which it is used and will be extremely easy to mount and to repair.

35 A further object is to present a magneto of this character having a simple and novel means for advancing and retarding the time of spark.

With these general objects in view and 40 others which will become apparent as the description proceeds, the invention resides in certain novel features of construction, combination and arrangement of parts which will be hereinafter more particularly 45 described and claimed.

In the accompanying drawings:

Figure 1 represents a vertical longitudinal sectional view taken substantially on the plane of the line 1—1 of Fig. 2.

50 Fig. 2 is a plan view of the parts shown in Fig. 1.

Fig. 3 is a vertical transverse section on the line 3—3 of Fig. 1, and

55 Fig. 4 is an end view of the device as seen from the breaker or spark gap end.

Referring now more particularly to the

drawings, wherein similar reference characters designate like parts throughout the views, it will be seen that the generating portions of the device are mounted between 60 the arms 1 and 2 of a substantially U-shaped frame 3, the arm 2 thereof having bolt apertures 4 whereby the same may be secured to the wall of an engine cylinder or the like. This arm 2 also carries a cylindrical plug 65 portion 5 having stationary and movable electrodes 6 and 7 respectively mounted therein and designed to be inserted through the plug opening of an engine cylinder.

The arms 1 and 2 and the plug portion 5 70 are provided with alined bearing openings, that in the first mentioned arm being designated by the numeral 8 and that in the latter parts by the numeral 9. A supporting shaft 10, one end of which is formed into 75 the electrode 7, is journaled in said alined openings 8 and 9. The electrode end 7 of the shaft 10 is provided with a head 11 which bears against the inner end of the plug portion 5 and carries a laterally extending arm 12 having a breaker point 13 thereon. This breaker point cooperates 80 with a stationary breaker point 14 on the end of the stationary electrode 6, the portion of the same which is within said cylindrical plug 5 being completely insulated therefrom. The end of the electrode 6 opposite to that carrying the breaker point 14 is provided with means for attaching a conductor thereto as indicated at 15.

90 The opposite end of the shaft 10, or that part which extends outwardly of the arm 1 is provided with a pin 16 and a coil spring 17. The spring surrounds the shaft and has one end secured to the arm 1 and the other 95 end engages the pin 16. This spring being of an expansive nature, the head 11 will be continuously urged into engagement with the end of the cylindrical plug 5, while the shaft 10 upon rotation in one direction will 100 be automatically returned to initial position when released.

The shaft 10 forms a support and 2 bearing surface for a sleeve 18, the intermediate portion of which has an armature or conductor carrying member 19 of conventional 105 form mounted thereon. As is customary in devices of this character this armature includes a winding of insulated wire, one end of which is grounded to the sleeve 18 while 110 the opposite end is fixed to a slip ring or equivalent part 20.

The armature is inclosed within a housing 21 also supported by the shaft 10 but mounted directly upon the sleeve 18 with which it is made independently rotatable as 5 a result of the bearings 22 located in the openings formed in its opposite ends. This housing 21 has a binding post or the like 23, the inner thereof carrying a suitable current collector 24 which is engaged with or 10 connected to said slip ring or equivalent part 20. The field element of this generator as is usual in ignition magnetos consists of one or more permanent horse-shoe magnets 25, the legs of which straddle the housing, 15 and consequently the armature 19, and are secured to the former.

Normally the housing 21 and the magnets 25 are stationary, the lines of force set up by the latter being cut by the conductor of 20 the armature when the same is oscillated. Movement of the armature in one direction is procured by a push rod 26 suitably actuated by the engine, and a finger 27 carried by a collar or other sleeve 28 fixed to and 25 surrounding a portion of the sleeve 18 disposed externally of the housing 21 and located between the arm 2 and the adjacent end of the latter. The sleeve 28 also has a pair of diametrically extending rocker arms 29 projecting therefrom at right angles to 30 its axis, and when the armature is inactive and stationary these rocker arms 29 extend in the direction of and lie in the same plane as spring arms 30. These latter arms 30 35 are formed integrally with the cover plate of one end of the housing 21.

The end of each of the rocker and spring arms has a pin 31 projecting therefrom to receive the attaching ends of return springs 40 32. One of these springs is secured to each pair of rocker and spring arms as most clearly shown in Figs. 2 and 3. Also from the latter figure it will be appreciated that as the push rod moves toward the finger 27 45 it will cause the clockwise rotation of the sleeves 28 and 18 together with the armature 19 until said finger has been shifted to such an extent that the contacting end of the push rod rides thereover, thereupon the springs 30, which have been placed under tension by 50 the disalignment of the rocker and spring arms, will contract and quickly snap the armature and parts carrying the same back to initial position.

55 One end of the other sleeve 28 is provided with a clutch face 33, and a clutch 34 is keyed to the shaft 10 for coöperation therewith. The cam action exerted by the clutch face on the clutch element 34 causes a slight 60 rotation of the shaft 10, and the electrode 8 with a result that the breaker points 13 and 14 are separated.

Although the housing 21 and the permanent magnets 25 are normally stationary, 65 they may be adjusted to various positions

on the sleeve 18 and locked in such positions. This is carried out by making the right portion of the frame 3 arcuate as shown in Figs. 3 and 4 and providing the same with a transversely extending slot 35 through which a 70 stem 36 extends. This stem is in the form of a threaded rod carried by the bottom of the housing 21 and has a nut 37 for engagement with the outer surface of said arcuate portion of the frame 3. By such an arrangement an advance or retard of the spark may be readily procured. Upon such partial rotation of the housing and magnets, proper relationship between the clutch face 33 and the clutch arm 34 is retained by having the 80 slot 35 disposed at an angle, other than a right angle, to the plane of the longitudinal axis of the shaft 10 (see Fig. 2).

The operation of the invention is briefly as follows: Assuming that the device has 85 been mounted upon an internal combustion engine and the conductor connectors 15 and 23 electrically united, movement of the push rod 26 will relatively slowly revolve the armature 19 in a clockwise direction as seen 90 from Figs. 3 and 4, this movement being continued until the ends of the push rod 26 and finger 27 disengage. Immediately disengagement takes place the springs 32 come into play and very quickly rotate the 95 armature in a counter-clockwise direction, the force of these springs being such as to give the armature sufficient momentum to carry it beyond its initial position, to which position it is immediately thereafter returned upon the loss of momentum. At the time of the overthrow of the armature beyond its initial position, it has attained its greatest velocity, and therefore the lines of force thrown out by the permanent magnets are being most rapidly cut by the conductor on the armature. Therefore at this 105 moment the electro motive force is greatest, and consequently the "break" between the points 13 and 14 should occur at this time. The clutch parts 33 and 34 are so arranged with respect to each other that they will engage and rock the shaft 10 upon the overthrow of the armature past its normal or 110 initial position. A spark of maximum intensity is thus obtained.

I claim:

1. In an electric generator, a frame, a rock shaft mounted in the frame, a field element, a conductor carrying element loosely mounted on said shaft, means for oscillating said conductor carrying element, a stationary electrode, a movable electrode carried by the shaft and normally engaged with the stationary electrode, coöperating clutch members on the shaft and conductor carrying element, and a spring urging said shaft longitudinally and revolvably in one direction.

2. In an electric generator, a supporting 130

- shaft, a field element mounted on said shaft, a conductor carrying element loosely disposed on the shaft within the field element, means for oscillating the conductor carrying element, means for collecting the induced current from the conductor carrying element, and means for shifting the elements longitudinally of the shaft and for revolubly moving the field element on the shaft independently of the conductor carrying element.
3. In an electric generator, a supporting shaft, a field element support on the shaft, a field element carried by the support, a conductor carrying element oscillatorily mounted on the shaft within the field element, means for oscillating the conductor carrying element, means for collecting the induced current from the conductor carrying element, coöperating clutch members on the shaft and conductor carrying element, and means for shifting the field element support revolubly about the shaft and longitudinally thereof.
- 25 4. In an electric generator, a relatively
- stationary frame, a rock shaft journaled in the frame, a movable electrode formed on the shaft, a stationary electrode carried by the frame and normally engaged by the other electrode, a field element support on the shaft, a field element disposed on the support, a conductor carrying element oscillatorily mounted on the shaft within the field element, means for oscillating the conductor carrying element, a clutch member carried by the conductor carrying element, a coöperating clutch member on the shaft, a spark adjusting member extending from the field element support, said frame having a slot, the plane of the axis of which extends at an angle other than at right angles to the plane of the longitudinal axis of the shaft, receiving the spark adjusting member, and means for clamping the spark adjusting member to the frame.

In testimony that I claim the foregoing I have hereunto set my hand at Wauwatosa, in the county of Milwaukee and State of Wisconsin.

FRANK H. SCHRYER.
